UNITED STATES PATENT OFFICE.

AXENTI S. CERKEZ, OF BACAU, ROUMANIA.

SNOW-PLOW.

No. 895,002.

Specification of Letters Patent.

Patented Aug. 4, 1908.

Application filed September 25, 1906. Serial No. 336,150.

To all whom it may concern:

Be it known that I, AXENTI S. CERKEZ, engineer, a subject of the King of Roumania, and a resident of Bacau, Roumania, have 5 invented certain new and useful Improvements in Snow-Plows; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

15 My invention relates to improvements in snow plows in which the snow is first carried upward upon an inclined plane and then carried sidewise or backwards.

The object of my improvements is to decrease the friction of the snow on the lateral walls of the plow, whereby the snow moves almost without any friction through the plow so that the apparatus cannot be choked. And for this purpose I construct the bottom and 25 the side walls, or their surface, of a material having a very low coefficient of friction, and to which snow does not easily adhere, such as varnished or polished wood, or enameled leather, or by causing said 30 surfaces to move backwards.

The invention further consists in an improved means to cut out the amount of snow corresponding to the dimensions of the plow, so that the plow will easily overcome the resistance offered by the snow. For this purpose I provide an iron saw in 35 front of the plow, which saw preferably consists of a steel wire, and which is actuated by the same motor which moves the side 40 and bottom walls of the apparatus.

In the accompanying drawings I have illustrated, as an example, an apparatus embodying my invention.

In said drawings:—Figure 1 is a perspective view of the plow, Fig. 2 is a plan of the same, Fig. 3, a longitudinal cross section of the same, Fig. 4, a partial cross section, illustrating the means to move the bottom cross bars, Fig. 5, a cross section 45 on the line A—B of Fig. 4, Fig. 6, a view illustrating the movable side walls, Fig. 7, a cross section on the line E—F of Fig. 6, and Fig. 8 a cross section on the line C—D of Fig. 6.

Similar letters of reference refer to similar parts throughout the different views.

The platform 1 of the apparatus is arranged as an inclined plane having its lower front edge slightly above the bottom. In order to prevent the snow from adhering on the bottom, where a stationary bottom is used, cross bars 2 are provided which move over the platform from its front side to its rear end, whereby the snow is scratched off and carried to the rear end of the plow. Said cross bars are moved by any preferred means.

In the example illustrated, they are provided with short arms 3 extending downwards through longitudinal slots 9 of the platform and connected to endless chains 4 below the platform. The latter is actuated by a toothed wheel 7 which is rotated from the main motor driving the plow. The cross-bars are preferably guided on longitudinal rails 5 (Fig. 3) arranged below the platform, rollers 6 being provided on the arms 3 to decrease the friction. The vertical walls 10, and also the bottom where the scratching bars 2 are not used, consist of a material of very low coefficient of friction, to which snow does not easily adhere or they may be covered with a layer of such a material. Experiments have shown that enameled leather is most appropriate for the purpose.

Further to avoid loss by friction 35 the side walls, or an apron constituting the side walls, can be made movable in such a way, as to move backwards with the speed of the snow passing through the plow. An example of what may be done in this direction is shown in detail in Figs. 6 to 8. On

the inner side of an apron 11 angle bars 12 are mounted within a certain distance from each other, which bars support two rollers 13, 14. The upper roller 13 rotates about a horizontal arm of the vertical angle bar 12, while the lower one, 14, rotates about a vertical arm. The angle bars 12, are connected, with their inner surfaces, to an endless chain 15, which is moved by a toothed wheel 16 which is actuated, by an intermediate chain and chain wheel mechanism, from the motor of the machine. The chain 15, therefore, carries along the angle bars and the apron 11. The angle bars are guided in U-irons 17, having their web portions arranged horizontally and their flange portions extending downwards. On the horizontal upper sur-

face of the web portions of said U-irons 17 the upper rollers 13 are guided, while the lower rollers 14 are guided between the downwardly extending flanges of the same whereby a lateral displacement is avoided.

Fig. 8 shows in what way the toothed wheel 16 with the chain 15 and the U-iron 17 is sunk in the vertical side wall, whereby the latter is smooth on its inner surface and does not increase the resistance offered to the snow.

The snow is carried over the inclined platform 1 and piled up on both sides of the road. For this purpose vertical cross walls are arranged on the upper plate 18 of the plow, whereby the snow is moved sidewise. In the example shown, said walls are secured to the plate 18 by studs 26 engaging bore holes 20 of the plate 18. Said studs and bore holes are, preferably, arranged in such a way, that the same cross wall can be arranged in both directions, so as to deflect the snow either to the right or to the left, or to both sides simultaneously. Also the cross walls are made of a material having a low coefficient of friction, or they may be provided with a movable apron.

On the front side of the plow a reamer 21 is arranged, whereby the snow is moved sideways, in case the snow is deeper than the height of the plow. At the back of the apparatus an auxiliary plow 22 is provided below the platform 23 for the guide. By this arrangement, the apparatus can easily be moved back again, in case the snow should fall back again on the road.

In order to facilitate the cutting out of the amount of snow of a cross section corresponding to that of the plow, I provide a saw 24 in front of the apparatus, which, in the present example, consists of a steel wire moved along the vertical side walls and, preferably, also along the front edge of the bottom 1. Said wire 24 is guided on rollers 25. In the example shown it is moved along the front edge of each wall two times.

The whole of the apparatus is mounted on a truck or frame work 27, having wheels 28. The latter are made of wood, or, if preferred, 50 of iron 29, covered on both sides with wood 30. Any snow that may adhere to the wheels is removed by scratchers 31.

On the upper sides of the apparatus, I prefer to provide wings, whereby the upper margin of the snow walls produced by the plow is pressed sidewise, so that the snow is prevented from falling down on the road.

Having thus described my invention, what I claim as new and desire to secure by Letters 60 Patent of the United States of America is:

1. In a snow plow, the combination with the frame work, of walls consisting of a material having a low coefficient of surface friction and having a movement with the snow 65 removed by said plow.

2. In a snow plow, the combination with the frame work, and the side walls, of an apron of enameled leather covering said side walls.

3. In a snow plow, the combination with the frame work, and the side walls, of an apron of enameled leather covering said side walls, and means to move said apron in the direction of the snow entering the plow.

4. In a snow plow, the combination with the frame work, and a platform provided with longitudinal slots, of cross bars arranged on said platform and adapted for movement upon the same, and means mounted below said platform to move said cross bars over said platform in the direction of the snow entering the plow, said cross bars having depending projections slidable in said slots and operatively connected with said moving means thereby to protect said moving means from the snow to be removed by said plow.

5. In a snow plow, the combination with the frame work, and the platform, of cross-bars arranged on said platform, an endless chain arranged below said platform, means slidably mounted upon and projecting below said platform to connect said cross-bars to said endless chain, and means to move said endless chain with its upper part in the direction of the snow entering the plow.

6. In a snow plow, the combination, with the platform, side walls, and the frame-work, of a steel wire, arranged in front of the forward margin of said side walls and platform, rollers guiding said wire, and means to rotate said rollers.

7. In a snow plow, the combination, with the frame work, a platform, and side walls, of cross-walls arranged vertically on said platform connected with the sides of the frame having means to arrange said cross-walls obliquely to the direction of the snow entering the plow for directing and ejecting the snow from the sides of said plow.

8. In a snow plow the combination of a frame, running gear therefor, walls constructed to facilitate the movement of snow in contact therewith, a platform provided with cross-bars adapted to be moved longitudinally of said platform, an endless cutting member adjacent the front edge of the plow, means to transmit motion to the same, vertical walls upon said platform adapted to be arranged obliquely thereof, a top to said plow, vertical walls adapted to be arranged obliquely upon said top and wings adapted to be projected from the sides of the plow to push back the snow from the path of the plow and an auxiliary plow at the rear end of the plow proper.

9. In a snow plow, the combination, with the frame work, a platform, side walls, cross walls extending obliquely across said platform, of wings extending laterally from the upper part of the side walls for causing the

snow removed by said plow to be deposited at the side of the road or track.

10. In a snow plow, the combination of a frame, running gear therefor, a platform provided with cross-bars adapted to be moved longitudinally of said platform, side walls provided with an auxiliary wall comprising a snow repelling surface and roller supporting members secured to said auxiliary wall, 10 rollers upon said roller supporting members, the side wall provided also with a track for

supporting said rollers and means for transmitting motion to said rollers and auxiliary wall.

In testimony, that I claim the foregoing as 15 my invention, I have signed my name in presence of two subscribing witnesses.

A. S. CERKEZ.
